UNITED STATES PATENT OFFICE

VINCENT G. APPLE, OF DAYTON, OHIO

ARMATURE

Application filed September 26, 1929. Serial No. 395,429.

This invention relates to armatures for dynamo electric machines and particularly to those having two layer bar windings and a commutator.

- 5 An object of the invention is to provide a structure wherein the ends of the inner layer of conductor bars are combined with an equal number of simple stampings to compose a commutator.
- 10 I attain this object by proceeding in the manner hereinafter described, the description being supplemented by the accompanying drawings wherein—

Fig. 1 is a cross section through Fig. 2 at 15 1—1 and shows the cross sectional contour of the bar stock which I employ for the winding of my armature.

Fig. 2 shows a length of bar stock which has been offset as one step in the making of 20 a turn of the winding therefrom.

Fig. 3 shows the offset bar Fig. 2 after it is further bent to compose a winding loop.

Fig. 4 is an end view of Fig. 3.

Fig. 5 is a perspective view of a core where- 25 in a proper number of loops Fig. 3 are assembled, the ends of the loops extending through and beyond the core.

Fig. 6 shows a single pair of the loop ends extending from a core, and a tool adapted to 30 bend the extending end of the inner layer bar inwardly toward the core axis.

Fig. 7 is an end view of the tool shown in Figs. 6 and 8 in position.

35 Fig. 8 shows the core with the single pair of bars after the extending end of the inner layer bar has been bent inwardly toward the axis of the core.

Fig. 9 is an end view of the core after all 40 of the inner layer bars have been bent inwardly like the single bar shown in Fig. 8.

Fig. 10 shows the outline of a sheet metal stamping which serves the twofold purpose of end connector and as part of a commuta- 45 tor segment.

Fig. 11 shows the stamping Fig. 10 after it is bent to form a connector.

Fig. 12 is an end view of the armature after the connectors shown in Fig. 11 have been assembled on the ends of the bars.

Fig. 13 is a vertical axial section through a mold which I employ for forming a core of insulation about the ends of the winding to compose a commutator thereof.

Fig. 14 is a transverse section taken at 55 14—14 of Fig. 13.

Similar numerals refer to similar parts throughout the several views.

To provide bar winding loops according to my invention I select bar stock of a cross sectional contour 20, Fig. 1 and offset it edge-wise as at 21, near the middle of its length, leaving the bar 22 somewhat shorter than the bar 23, beveling the end of the bar 23 as at 25, and bending the bar at 21, 26 and 27 to form the loop herein generally designated by the numeral 28, (see Figs. 3 and 4), wherein the bar 22 is adapted to compose a half turn of the winding and be located in the outer layer thereof, and the bar 23 is 70 adapted to compose a half turn of the winding and be located in the inner layer thereof.

Fig. 5 shows a structure comprising a core 30 having a plurality of winding apertures 31 into which an equal number of loops 28 have been assembled, so that the bars 22 and the bars 23 extend through and beyond the end of the core in two concentric cylindrical rows, the bars of the inner row extending beyond the core farther than the bars of the 80 outer row.

By reference to Fig. 5 it will be seen that the spaces 32 between bars 23 are considerable wider than are ordinarily left between adjacent bars of a commutator, and since the 85 commutator is to be composed mostly of these bars, the spaces 32 are preferably reduced in width, and this may be accomplished most readily by reducing the diameter of the cylindrical row of bars 23.

For clearness, in Fig. 6, the core 30 is shown with but a single pair of bars 22 and 23. A tool 33 has an opening 35 (see end view Figs. 7) adapted to slide easily over bar 23. Means not shown is provided to move the tool 33 inward and at the same time toward the core, keeping the opening 35 at all times parallel to the armature axis, offsetting a small part of the bar as at 36 and bringing the remainder to the position shown in Fig. 8. And while but a single tool 33, bending but a single bar 23 is shown, a machine wherein a plurality of tools 33 operate simultaneously to offset all of the bars 23 as at 36, Fig. 8, is preferably employed in actual practice. When the entire number of bars 23 have been offset as at 36, Fig. 8, the ends will be arranged in a cylindrical ring of relatively small diameter, with relatively narrow spaces 37 between the ends, (see end view Fig. 9). Winding turns may now be completed by connecting bars of one layer to angularly spaced apart bars of the other layer in pairs, and for this purpose special end connectors are provided.

The blank Fig. 10 is preferably punched from sheet metal but it may be made by bending a length of strip stock edgewise to a right angle as at 38, if desired. The limb 40 of the angle has its end beveled at 25 to correspond to the beveled end 25 of the bar 23. Limb 40 is preferably of the same width as the bar stock composing the bar 23, while the other limb 42 may be wider if desired.

Fig. 11 shows how a blank Fig. 10 is bent to form a connector 43 wherein the limb 40 remains the same but the limb 42 is bent to involute form with its end further bent to form an eye 45 adapted to fit over the end of a bar 22.

In Fig. 12 a number of connectors 43 equal to the number of loops 28 are shown in place with limbs 40 arranged alongside of bars 23 in pairs, a limb 40 and a bar 23 together composing a commutator segment 44 and with the eyes 45 placed over, and electrically joined to the ends of the bars 22. The dimensions of the several parts must be such that even after the limbs 40 have been inserted in the spaces 37, Fig. 9 there will still be left a sufficient space 46, Fig. 12, between adjacent segments. The eyes 45 may be readily joined to the ends 22 by welding, soldering or by any equivalent means since they are at the outer diameter and at the end where they are readily accessible, and in this respect my improved armature is quite different from one of conventional design, wherein involute end connectors are employed for connecting both the outer and inner layers of conductor bars to commutator segments, for there as is well known the joints which must be made between the involute end connectors and the inner layer bars are most inaccessible. The limbs 40 may be soldered, welded or similar-

ly joined to the bars 23 to compose the segments 44 or they may be held in intimate electrical contact one with another by the core of insulation which is afterward molded about them.

Figs. 13 and 14 show the mold 47 into which I place the structure Fig. 12 to mold a core of insulation about the segments 44 and their beveled ends 25 and about the connectors 43 to hold them rigidly in proper spaced relation and to keep them insulated one from another. The mold comprises a base 48 carrying a central core 49. A cylinder 50 is concentrically supported on base 48. A ring 51 is fitted to revolve freely about cylinder 50. In the lower edge of ring 51 bevel gear teeth 52 are cut, while the upper edge contains a spirally cut scroll 53. A plain shoulder 54 over which the teeth 52 do not extend limits downward axial movement of the ring. A cylinder 55 having a thick flange 56 at its lower end is fastened by screws 57 to the top of cylinder 50. The thick flange 56 has cut in its lower side a series of radially extending grooves 58 each of which contains a jaw 59 having a tang 60 at its inner end (see Fig. 14) and scroll teeth 61, adapted to mesh with scroll 53 of ring 51, in its lower edge. A hand wrench 62 carries pinion 63 adapted to mesh with teeth 52 of ring 51 to revolve the ring and by means of the scroll 53 to move jaws 59 radially inward or outward, depending on the direction in which the wrench 62 is turned. A plunger 64 is slideable into cylinder 55 and over central core 49. The mold operates as follows:

With plunger 64 removed from the cylinder 55 and the mold body 50 removed from base 48 the structure Fig. 12 is placed over central stud 49. With wrench 62 jaws 59 are moved slightly in a radially outward direction and the mold body is then placed over the armature on to the base 48 with tangs 60 extending slightly between segments 44. A clearance space 65 permits the segments 110 to spring radially outward slightly to increase the space between them and allow tangs 60 to enter freely.

Wrench 62 is now turned to move jaws 59 radially inward to clamp the two parts 23 and 40 of a segment tightly together as in a vise. A proper quantity of unmolded insulation is then put into cylinder 55 and, with the plunger 64, is compacted and hardened between and about the segments 44 and the beveled ends 25 to compose a commutator and through and about the connectors 43 to hold them rigid. When jaws 59 are withdrawn the armature and completed commutator are readily removed from the mold.

Having described my invention, I claim:

1. In an armature having a core and a two layer bar winding, a turn of said winding comprising a loop and an end connector, said loop comprising a bar of the outer layer and

an angularly spaced apart bar of the inner layer joined together at one end, the outer layer bar being considerably shorter than the inner layer bar, both bars extending through, 5 and the inner layer bar considerably beyond, the end of the core, the inner layer bar being offset radially inward at the end of the core leaving the remainder of the extending end axially parallel but closer to the core axis, 10 and said end connector joining the end of the outer layer bar to an angularly spaced apart axially parallel end of another inner layer bar.

2. In a dynamo electric machine armature, 15 a core, a two layer bar winding extending through and beyond the core in two axially parallel cylindrical rows, the inner row extending considerably farther beyond the end of the core than the outer row and being radially offset with the ends in a cylindrical row of considerably less diameter than the core contained portion, and connectors joining the 20 ends of the bars of the outer row to the radially offset ends of angularly spaced apart bars of the inner row.

3. In an armature, a core, a two layer bar winding extending through and beyond the core in two axially parallel cylindrical rows, the inner row extending considerably farther 30 beyond the end of the core than the outer row and being radially offset with the ends in a cylindrical row of considerably less diameter than the core contained portion and composing the segments of a commutator, and connectors extending from the outer ends of 35 the inner layer alongside each radially offset bar end, thence outwardly to the end of an angularly spaced apart bar of the outer layer.

40 4. In an armature, a core, a two layer bar winding extending through and beyond the core in two axially parallel cylindrical rows, the inner row extending considerably farther beyond the end of the core than the outer row 45 and being radially offset with the ends in a cylindrical row of considerably less diameter than the core contained portion and composing commutator segments, and connectors of right angle form each having one limb 50 lying alongside a commutator segment, and the other limb extending in an involute path and having its outer end joined to the end of an angularly spaced apart bar of the outer layer.

55 5. In an armature, a core, a two layer bar winding extending through and beyond the core in two axially parallel cylindrical rows, the ends of the outer row being cut off straight and the ends of the inner row being beveled, 60 the inner row extending considerably farther beyond the end of the core than the outer row and being radially offset with the ends in a cylindrical row of considerably less diameter than the core contained portion and composing 65 commutator segments, connectors having

one part adapted to lie alongside each segment in electrical contact therewith and another part extending outwardly and electrically joining to the end of an angularly spaced apart bar of the outer layer, and a core 70 of molded insulation extending about the ends of the outer layer bars and the outwardly extending ends of the connectors, and between and about the segments and about the beveled ends thereof thereby to compose a commutator 75 for said armature.

In testimony whereof I affix my signature.
VINCENT G. APPLE.
